[57] CLAIM

The ornamental design for a mobile electrostatic air filter, as shown and described.

DESCRIPTION

FIG. 1 is a right side elevational view of a mobile electrostatic air filter showing our new design;
FIG. 2 is a left side elevational view thereof;
FIG. 3 is a front elevational view thereof;
FIG. 4 is a rear elevational view thereof;
FIG. 5 is a top plan view thereof; and,
FIG. 6 is a bottom plan view thereof.

FIG. 2

FIG. 1

FIG. 4

FIG. 3

FIG. 6

FIG. 5

UNITED STATES PATENT AND TRADEMARK OFFICE
CERTIFICATE OF CORRECTION

PATENT NO. : Des. 329,081

DATED : September 1, 1992

INVENTOR(S) : Alf I. S. Jonasson and Per N. Hedlund

It is certified that error appears in the above-identified patent and that said Letters Patent is hereby corrected as shown below:

Item [54] should read as follows:

--MOBILE ELECTROSTATIC AIR FILTER--

Signed and Sealed this

Fourteenth Day of September, 1993
